UNITED STATES PATENT OFFICE.

ARTHUR E. GUMPRECHT, OF STEAMBOAT SPRINGS, COLORADO.

ENGINE.

1,276,056.

Specification of Letters Patent. Patented Aug. 20, 1918.

Application filed April 9, 1917. Serial No. 160,766.

To all whom it may concern:

Be it known that I, ARTHUR E. GUMPRECHT, a citizen of the United States, residing at Steamboat Springs, in the county of Routt and State of Colorado, have invented certain new and useful Improvements in Engines, of which the following is a specification, reference being had to the accompanying drawings.

10 This invention relates to certain improvements in engines and has relation more particularly to a device of this general character embodying rotary abutments or pistons; and it is an object of the invention to provide novel and improved means whereby leakage between the pistons or abutments and the coacting walls of the casing is substantially entirely eliminated.

15 It is also an object of the invention to provide an engine of a novel and improved construction wherein the exhaust may be employed for braking the same.

A further object of the invention is to provide a novel and improved engine of an internal combustion type wherein the piston has unresisted rotary movement with a minimum of friction and without back pressure created by compression.

20 A still further object of the invention is to provide a novel and improved engine of an internal combustion type including a rotary piston together with means whereby the charge may be compressed.

25 A still further object of the invention is to provide a novel and improved engine including two rotatable pistons and wherein the supporting shaft for one of the pistons is provided with yieldable bearings to compensate for the expansion of the metal of

40 which the stator or casing may be produced. The invention consists in the details of construction and in the combination and arrangement of the several parts of my improved engine whereby certain important advantages are attained and the device is rendered simpler, less expensive and otherwise more convenient and advantageous for use, all as will be hereinafter more fully set forth.

45 The novel features of the invention will hereinafter be definitely claimed.

In order that my invention may be the better understood, I will now proceed to describe the same with reference to the accompanying drawings, wherein—

50 Figure 1 is a view in elevation with a part

in section of an engine constructed in accordance with an embodiment of my invention;

Fig. 2 is a view in elevation of the engine as disclosed in Fig. 1 with a side plate removed and the shafts of the rotor in section;

Fig. 3 is a view partly in top plan and partly in section of the engine as set forth in the preceding figures;

Fig. 4 is a fragmentary sectional view taken through one of the pistons as herein embodied;

Fig. 5 is a fragmentary view taken through one of the pistons on a line at right angles to that of Fig. 4;

Fig. 6 is a view in top plan of a plate coacting with a wing of a piston as herein disclosed;

Fig. 7 is an enlarged fragmentary sectional view illustrating in detail the controlling means for the fuel;

Fig. 8 is a diagrammatic view illustrating an igniting system as herein embodied;

Fig. 9 is an elevational view illustrating an engine constructed in accordance with a further embodiment of my invention;

Fig. 10 is an enlarged fragmentary vertical sectional view taken through the upper portion of the engine as disclosed in Fig. 9;

Fig. 11 is a sectional view taken substantially on the line 11—11 of Fig. 9;

Fig. 12 is a sectional view taken substantially on the line 12—12 of Fig. 9; and

Fig. 13 is a rear elevational view of the cam coacting with the operating lever for the slide valve of the compression chamber as herein set forth.

As disclosed in the accompanying drawings, C denotes a casing provided with two substantially cylindrical chambers A and B having communication one with the other, and disposed transversely of the casing at the longitudinal center of each of the chambers A and B is a shaft 1 supported by the bearings 2 and 3 carried by the side plates 4 and 5, respectively, of the casing. The bearings 3 are capable of limited longitudinal movement, said movement being under control of the expandable members 6 positioned at opposite sides of each of the bearings 3. By this arrangement it will be at once self-evident that compensation will be afforded for the expansion or contraction of the metal of which the casing C may be composed or more particularly the side plate 5.

The portions of the shafts 1 adjacent the

bearings 2 are operatively connected one with the other through the medium of the meshing gears 7 whereby it will be at once perceived that the shafts 1 will rotate in unison but in reverse directions. It is also to be noted that the gears 7 are of equal ratio so that the axial speed of the shafts 1 will be identical.

Keyed to each of the shafts 1 is a piston P 10 substantially cylindrical in form and of a diameter materially less than the mean diameter of the chamber A or B in which it may be positioned, and the periphery of said piston is provided with a transversely disposed recess or pocket 8 extending entirely thereacross and one of the side walls of said recess is defined by the radially disposed wing or abutment 9. Each side of the piston P intermediate the recess 8 and the wing 20 or abutment 9 has coacting with its peripheral marginal portion the packing members 10. Each of these members 10 are substantially L-shaped in cross section so as to partially overlie the adjacent marginal 25 portion of the side face of the piston P.

Coacting with the member 10 are the expandible members 11 which serve to constantly urge the member 10 toward the adjacent side plate of the casing C so that leakage is prevented. It is also to be noted that each of the members 10 extends inwardly and substantially radial at the ends of the side wall of the recess 8 opposite to the wall thereof defined by the wing or 35 abutment 9.

Each side of the piston P is also provided with an annular recess 12 concentric to the shaft 1 and in which is positioned the packing ring 14 also constantly urged toward 40 the adjacent side plate of the casing C by the expandible members 15.

The outer end of each of the wings or abutments 9 is provided with an overlying plate 16 provided with the inwardly directed 45 ribs 17 extending within recesses 18 produced in the outer face of the wing or abutment 9. The ribs 17 are positioned adjacent the opposite longitudinal margins of the plate 16. At substantially its transverse 50 center the plate 16 is provided with the flange 19 substantially T-shape in cross section and positioned within a correspondingly formed groove or channel 20 produced in the outer end of the abutment or wing 9.

55 The groove or channel 20 is of a length in excess of the width of the flange 19 so that the plate 16 will have limited independent movement so that the same will be effectively engaged with the peripheral wall of the 60 chamber A or B by centrifugal force as the piston rotates.

Each side of the wing or abutment 9 is provided with a radial groove or channel 21 extending inwardly of the adjacent side of 65 the piston P and in communication with the

annular recess 12 hereinbefore referred to. The ring 14 seated within the recess 12 is provided with teeth 22 extending within the inner end portion of said channel or recess 21.

In mesh with the teeth 22 are the teeth 23 carried by the packing plate 24 while the opposite end of said plate 24 is interlocked with the adjacent end of the flange 19 hereinbefore referred to. The plate 24 is also adapted to be maintained in constant contact with the adjacent side plate of the casing C through the medium of the expandible members 25.

The side plate 5 at substantially its longitudinal center is provided with the vertically spaced intake port 26 and exhaust port 27. The wall of the intake port 26 is provided with a recess 28 into which extends the 85 sparking plug 29 whereby it will be perceived that the recess 28 serves as the igniting chamber.

In communication with the port 26 is the pipe 30 in communication with the atmosphere and preferably having its free end portion angularly disposed and in substantially parallelism with the side plate 5. The inner end portion of the pipe 30 at a predetermined distance outwardly of the port 26 is provided with the valve seat 31 with which 90 coacts the valve 32 which is normally urged toward the seat 31 through the medium of the expandible member 33 herein disclosed as a coil spring encircling the outer end portion of the stem 35 of the valve 32 and interposed between the pipe 30 and the enlargement or head 36 carried by the outer end of the stem 35.

In the operation of the engine as herein embodied the abutments or wings 9 after 100 passing the intake port 26 serve to draw a charge through said port. In order to assure the proper entrance of the gas without the creation of a slight vacuum I have found it of importance to provide means for positively unseating or opening the valve 32. As herein embodied, I employ the arm 37 pivotally mounted intermediate its length with the outer end of the post 38 carried by the side plate 5.

The arm 37 is substantially sigmoidal in form and one terminal of the arm 37 overlies and engages the outer end portion of the stem 35, while the opposite end portion of the arm 37 is in contact with the cam 39 carried by the adjacent end portion of one of the shafts 1. It is to be understood that the cam 39 has its high point so positioned as to assure the unseating or opening of the valve 32 at the proper time and to maintain the same unseated or opened for the requisite period. It is to be understood that the charge delivered within the casing C is only of atmospheric pressure.

W denotes a vertically disposed well car-

ried by the plate 5 having its upper end open and having arranged therein a nipple 40 having its lower end terminating in close proximity to the lower or closed end of the well and having its upper or opposite end extending within the pipe 30. Disposed through the pipe 30 and coacting with the discharge end of the nipple 40 is the needle valve 41 whereby the quantity of fuel delivered within the pipe 30 may be readily and conveniently regulated.

In communication with the well W through the bottom thereof is the pipe 42 leading from a suitable source of fuel supply, preferably gasoline, and interposed in said pipe is the pump 43 including the reciprocating piston 44 operatively engaged, as at 45, with the adjacent end of the second shaft 1 whereby it will be perceived that during the operation of the engine, fuel will be delivered within the well W. Also in communication with the well W through a side thereof is the overflow pipe 46 whereby a predetermined level of the fuel within the well W is maintained. The pipe 46 serves to return the overflow to the source of fuel supply.

In communication with the port 27 is the exhaust pipe 47 and interposed in said pipe 47 is the valve 48. When the valve 48 is closed it will be understood that the movement of the pistons within the casing C will be retarded and brought to a standstill. In practice I have found it of particular advantage to provide this means for causing the exhaust to serve as a braking medium. The valve 48 may be operated in any desired manner as the requirements of practice may dictate.

In the form of invention illustrated in Figs. 9 to 13, I disclose an embodiment of my invention wherein the charge is compressed. In this embodiment of my invention the casing C and the pistons P' are of substantially the same construction as has been set forth relative to the casing C and the pistons P.

Carried by the top of the casing C' at substantially the center thereof is the compression chamber 49 in communication with the adjacent portions of the chambers A' and B' through the medium of the restricted ports 50. Coacting with the ports 50 is the slide valve 51 extending exteriorly of the compression chamber 49 and provided with a rack 52 with which is engaged the pinion 53 carried by the rock shaft 54. The rock shaft 54 is provided with the arm 55 with which is engaged the lever 56 coacting with the cam 69. As herein embodied, the cam 57 is driven by one of the shafts 1' at a ratio of 3 to 1.

In communication with one of the chambers A' or B' is an air intake port 58 and in communication with the second of said

chambers A' or B' is the gas intake 59. Coacting with the intake 59 is the valve 60 having coacting therewith a spring 61 of sufficient strength to create a vacuum so as to prevent the volume of gas being too great for one explosion. It is to be understood that the charge of gas is drawn in through the intake 59 at the first revolution of the pistons P'.

Coacting with the intake port 58 is the valve 62 with which coacts the spring 63 of a resistance greater than that of the spring 61 so that the valve 62 will not open on the first revolution of the pistons P'. The valve 62 is adapted to be positively opened upon the second revolution of the pistons P' through the medium of the cam 57 in a manner substantially the same as has been set forth relative to the positive operation of the intake valve 32.

In communication with one of the chambers, as A', is a port 64 in communication with the compression chamber 49 through the medium of the pipe 65. Coacting with the port 64 is the spring-pressed valve 66 adapted to be positively opened under the influence of the cam 57 in substantially the same manner as the valve 62. The valve 66 is adapted to be opened when the pistons are on their second stroke so that the gas and air admitted through the ports 58 and 59 will be compressed and forced up into the compression chamber 49. Upon the next revolution of the pistons P' the slide valve 51 will be adjusted into open position and the mixture enter within the chambers A' and B' intermediate the wings or abutments 9 through the ports 50.

As herein embodied, the chamber A' adjacent the port 64 is provided with the exhaust port 67 with which coacts the spring-pressed valve 68. The exhaust port 67 is adapted to be opened after the revolutions of the pistons P' immediately following the explosion and the valve 68 is also positively opened or unseated through the medium of the cam 69 driven by the shaft 1' disposed through the chamber A' and in a manner as has been similarly set forth relative to the remaining valves. The valve 60 is also spring-pressed and is adapted to be positively opened under the influence of the cam 57 referred to.

In Fig. 8 I disclose an igniting system for the embodiment of the invention as disclosed in Figs. 1 to 7 inclusive, and wherein in the plug 29 is electrically connected in a conventional manner with the source E of electrical energy and wherein is interposed a circuit closer comprising a contact a carried by a shaft 1 and which is adapted to engage upon each revolution of the shaft 1 the second contact b.

The igniting system for the spark plug 29 in the embodiment of my invention as

disclosed in Figs. 9 to 13 inclusive is substantially the same as has been set forth relative to the first embodiment of my invention except the movable contact will be carried by a cam 57 or 69 so that the circuit will be closed upon every third revolution of a shaft 1^a.

From the foregoing description, it is thought to be obvious that an engine constructed in accordance with my invention is of an extremely simple and comparatively inexpensive nature and is particularly well adapted for use by reason of the convenience and facility with which it may be assembled, and it will also be obvious that my invention is susceptible of some change and modification without material departure from the principles and spirit thereof and for this reason I do not wish to be understood as limiting myself to the precise arrangement and formation of the several parts herein shown in carrying out my invention in practice, except as hereinafter claimed.

I claim:

- 25 1. A device of the character described comprising a casing, a compression chamber in communication therewith, a valve for controlling the communication between the casing and the compression chamber, a conduit in communication with the casing and the compression chamber, a piston within the casing, a valve interposed within the conduit, said casing being provided with an air intake, a gas intake and an exhaust, 30 valves coacting with said gas intake, air intake and exhaust, and means for intermittently opening said valves.
2. A device of the character described comprising a casing, a compression chamber in communication therewith, a valve for controlling the communication between the casing and the compression chamber, a conduit in communication with the casing and the

compression chamber, a piston within the casing, a valve interposed within the conduit, said casing being provided with an air intake, a gas intake and an exhaust, valves coacting with said gas intake, air intake and exhaust, and means for intermittently opening said valves, said means serving to intermittently operate the valve controlling the communication between the compression chamber and the casing.

3. A device of the character described comprising a casing, a compression chamber in communication therewith, a valve for controlling the communication between the casing and the compression chamber, a conduit in communication with the casing and the compression chamber, a piston within the casing, a valve interposed within the conduit, said casing being provided with an air intake, a gas intake and an exhaust, and means for intermittently opening said valves, said means serving to maintain the valves 65 in the intake port and in the conduit open during the same period.

4. An engine of the class described comprising a casing provided with an inlet port in a side wall, said port being provided in a 70 wall exterior of the casing with an elongated and substantially horizontally disposed recess, an inwardly opening valve coacting with the inlet port and positioned in advance of the recess in the port, a piston 75 moving within the casing and operating to draw a charge within the casing through the inlet port, and a spark plug extending within the inner end portion of the recess.

In testimony whereof I hereunto affix my 80 signature in the presence of two witnesses.

ARTHUR E. GUMPRECHT.

Witnesses:
